DESIGN FOR A HAT BANDING OR SIMILAR ARTICLE

Lou Greenspan, New York, N. Y.

Application September 12, 1942, Serial No. 108,219

Term of patent 3½ years

To all whom it may concern:

Be it known that I, Lou Greenspan, a citizen of the United States of America, residing in New York city, county of New York, and State of New York, have invented a new, original, and ornamental Design for a Hat Banding or Similar Article, of which the following is a specification, reference being had to the accompanying drawing, forming part thereof, wherein the figure of the drawing is a plan view of a piece of hat banding or similar article showing my new design.

I claim:

The ornamental design for a hat banding or similar article, substantially as shown.

LOU GREENSPAN.
